THREAD ADVANCING REEL

Richard W. Stanley, Lakewood, Ohio, assignor to
 American Viscose Corporation, Wilmington,
 Del., a corporation of Delaware

Original application October 26, 1944, Serial No.
 560,445, now Patent No. 2,447,143, dated Au-
 gust 17, 1948. Divided and this application
 February 6, 1948, Serial No. 6,710

2 Claims. (Cl. 28—71.6)

1

This invention relates to thread-advancing reels which may be used for the production of a yarn store which is continuously advanced axially of the periphery of the reel, during which time it may be subjected to fluid treatment in the manner and for the purposes conventional in the art. This application is a division of my copending application Serial No. 560,445, filed October 26, 1944, now Patent 2,447,143, August 17, 1948.

It is a particular object of this invention to provide an improved thread-advancing reel. It is a further object of this invention to devise a reel which is adaptable to either a cantilever or double end supported structure. It is a further object of the invention to provide a reel of this type based upon a structural principle which, when embodied in a reel of considerable axial length results in substantially uniform efficiency in thread-advancing action throughout the length of the reel, and, at the same time, is adapted to operation at high speeds of rotation of the reel. A further object is to provide a reel with a multispeed drive at one end and means accessible to the operator at the other end for shifting from one speed to another. Further objects and advantages of the invention will be apparent from the drawings and description thereafter of hereinafter.

In the drawings illustrative of the invention—

Figure 1 is a mid-section taken axially through one embodiment of the reel of this invention on line I—I of Figure 2;

Figure 2 is a section taken on line II—II of Figure 1; and

Figure 3 is a section taken on line III—III of Figure 1.

In general, thread-storing, thread-advancing reels of this invention comprise a concentric set of spaced, longitudinally extending bars and an eccentric set of spaced, longitudinally extending bars interdigitating with and alternating between the bars of the first set. The bars in the non-concentric set are supported on a rigid member rotatably mounted on an axis both eccentric and askew with respect to the axis of the concentric set of bars and are individually connected to the member by universal joints which allows of axial displacement of the bars individually with respect to the remaining bars in the set. This articulated mounting is preferably of such a character that the main relative movement occurs along spherical surfaces.

Referring more particularly to Figures 1 and 2, the concentric set of longitudinally extending

bars 2 extend at one end into suitable recesses 3 of the flange or spider 4 while the other ends are interlocked with an annular rib 5 of a flange or spider 6. The cylindrical cage of bars 2 may be clamped between end flanges or spiders 4 and 6 by suitable spaced cap screws 7 which are associated with springs 8. The system comprising the cylindrical cage of bars 2 and flanges 4 and 6 constitutes a housing which 10 may have any axial length desired, and which may house the actuating mechanism for the other set of interdigitating bars 9. This housing is supported for rotation with respect to a stationary hollow shaft 10 by means of suitable bearings 11. Flange 4 may be provided with a plurality of projections 12 which are adapted to fit in corresponding sockets 13 of a coupling 14 rotatably mounted in the stationary frame 15.

A two faced friction clutch 16 is fixedly secured on slidably mounted shaft 17 which extends to both side thereof with one end recessed to receive a spring 18 which urges the shaft and clutch to the left as viewed in Figure 1. The other end of the shaft is provided with a splined connection at 19 so that it can slide axially of the coupling 14 and at the same time transmit rotation to the coupling 14. Gears 20 and 21 are freely rotatably mounted on the shaft 17 at each side of the clutch 16 and have clutch faces 22 adapted 20 to cooperate with the adjacent face of the clutch 16. While the clutch faces are of conical shape as shown, they may instead be flat disks or annuli. Any type of clutch may be substituted but preferably a type is used which may slip 25 when a predetermined load is exceeded, whether this be a positive or friction drive type of slip clutch or equivalent device.

The gears 20 and 21 are adapted to be driven at different speeds by gears 20a and 21a respectively. A rod 23 having enlarged diameters adjacent each end and a rib at 24 extends through the hollow shaft 10 which is held stationary by the key 25 in the flared member 26 which fits on the bearing 27. The rod 23 has a pin 28 30 which projects outwardly from it and is arranged to cooperate with the slotted way in a stationary sleeve or hub 29. By turning the hand knob 30 fixed on the end of rod 23, the rod may be shifted from the central branch slot in which the clutch 16 is disengaged to and from the extreme branch slots in which the reel is driven at high and low speed respectively by virtue of the connection of the clutch to the gears 20 and 21 respectively. A thrust bearing 31 is 35 provided to permit relative rotation of shaft 17

and rod 23. This arrangement makes the control of the clutch readily accessible from the discharge end of the reel which projects away from the driving connections so that an operator can readily shift to low speed for lacing up the reel and then to high speed for normal operation. When a large battery of such reels are associated in a common filament production or processing machine, the driving connections may all be associated with a couple of common drive shafts housed in an extension of the frame 15 and the reels may be arranged closely together on parallel axes without detriment to the individual reel driving control and its accessibility.

The bars 9 in the eccentric set are of composite structure, the bar proper 9 being fixedly secured to a reinforcing beam 32 which has two projections 33, one at each end and each end of the beam is adapted to be connected to a corresponding rotatable member 34 and 34' respectively through a universal connection. The member 34' may be of a construction identical with that shown for member 34 and in that event both should be mounted on bearing sleeves having paralleled axes eccentric and inclined with respect to the axis of shaft 10. In the preferable construction shown, however, only one of the members, namely 34 is mounted on an askew and eccentric sleeve 35 while the other member 34' is mounted on a sleeve 35' which is eccentric only with respect to the shaft 10 so that member 34' follows the motions of member 34 transmitted by the bars 9 (or their beams 32).

The universal connection between the members 34, 34' and the bars 9 is obtained by the use of spherical balls 36 which operate within spherical recesses provided in the outer periphery of the members 34 and 34' and inwardly faced spherical recesses formed in each of a ring of relatively slidable blocks 37 fixedly secured on the projections 33 of the beams 32 attached to bars 9. Because of the askew axis which controls the motion of members 34 and 34' just sufficient space is preferably provided between the adjacent relatively slidable surfaces of blocks 37 to permit rocking or oscillatory movement of the blocks about an axis extending radially with respect to the eccentric axis of the bars 9. If desired however, these surfaces may be spaced entirely out of contact with each other. A stiff, resilient shroud or cover 38 is fixedly secured to each of the members 34 and 34' and maintains the blocks 37 seated on the balls 36 while permitting sufficient motion between the blocks and itself to assure efficient articulation. The inner faces of the blocks 37 are spaced at all times from the outer faces of the members 34 and 34' so that there is no binding contact between them. To permit the member 34' to follow freely the motions of member 34, the inner bearing surface 38a of the outer race of the ball bearing supporting the member 34' on the eccentric sleeve 35' is made of spherical shape, though other expedients may be resorted to for this purpose. Both the members 34 and 34' as well as their associated shrouds 38 are provided with openings 7b to permit unobstructed passages of tie rods 7.

Where it is desired to protect the main operating parts from any possibility of clogging and corrosion when the reel is used for subjecting the filamentary material to liquids, a flexible sealing membrane 39, such as of rubber or synthetic rubber, may be secured about the projections 33 of the articulated supporting means for

the non-concentric bars and to the ends of the concentric cylindrical cage as shown. Similarly grease for lubricating the mechanism can be kept out of contact with the thread manipulating bars.

As shown, the flange 6 overhangs the outer rim 40 of the stationary flared member 26. The outer peripheral surface of the member 26 preferably slopes inwardly from its outer rim 40 to a generally cylindrical portion 41, which serves to hold any accumulation of thread formed after breakage of the thread being handled by the reel or during lacing up of the reel or any machine comprising the reel. Occasionally, stray filaments also tend to gather on this member 26. The member 26 has a surface 41 of sufficient axial extent to provide adequate storage space and ready access for the operator to remove the accumulated filaments or threads at his convenience without danger of injury to his hands, and without the necessity either of stopping the reel or of giving it immediate attention when the above-mentioned emergencies arise.

In operation, the skew member 34 causes substantial axial motion of the bars 9, such motion being imparted individually to each of the bars 9 by virtue of the individual universal joints between them and the member 34. By virtue of the eccentricity of the articulated supporting means and the bars 9, the axial to and fro motion of the bars imparted by the askew member 34 is combined with a radial component of motion which alternately causes first the protraction of the bars 9 outside the periphery of bars 2 and then their recession within that periphery, thereby resulting in the advancing of the thread axially of the reel.

The reels may be of any length desired and when relatively long compared to their diameter, the concentric bars 2 may be reinforced by annular members 42 which are arranged to pass through apertures 43 made in the bars 9 and their reinforcing beams 32 without interfering with the motions of the bars 9.

The form of universal connection which essentially comprises a ball and socket joint assures that the composite swiveling of each bar 9 about two axes, one transverse to the eccentric axis of the bar and to the plane of the bar and the other lying in the plane of the bar and extending radially with respect to the eccentric axis of the bar, occurs in a common spherical surface without any possibility of binding or twisting the elements of the joint into a distorted shape which would tend to bind or interfere with one or more of the components of the composite swiveling motion. Relatively little sliding motion occurs between the elements of the articulated system and they are readily and reliably lubricated to minimize frictional losses. Another outstanding advantage of the preferred reel construction of this invention is the use of a single askew member 34 rotating on an axis eccentric and askew to that of the concentric bars 2 for actuating the bars 9 and mounting another member rotatable on an eccentric axis in such a manner that it follows the askew motion of the member 34. This not only simplifies the reel construction but prevents the excessive wear and damage that may result when the eccentric and askew axes of two such members deviate more or less out of parallel arrangement. The reel of the present invention combines ruggedness and sturdiness of construction with simplicity and negligible sliding friction. The resulting contact of the bars

with the thread avoids entirely any possibility of appreciable sliding or shimmmying motion of the bars with respect to the thread and consequently produces a processed thread of outstanding uniformity free of partially worn areas and irregularly stretched and tensioned lengths.

The various parts of the reel may be made of any particular materials desired. The construction lends itself readily to making the bars 2 and 9 of materials which offer the most satisfactory bearing surfaces for the filamentary material to be handled thereby from the standpoint of smoothness, durability, and/or resistance to corrosion under the influence of any liquids with which the filamentary material is to be treated while being advanced longitudinally of the reel, without making the remainder of the reel thereof. This is of tremendous importance from the view point of initial and depreciation cost of such reels, since materials which best meet the requirements specified are generally considerably more expensive than related materials which would be fully adequate for all portions of the supporting structure of the reel other than those intended to contact the filamentary material. Thus, parts 2 and 9 may be made of porcelain, Durez (a phenol-formaldehyde resin), Alsimag (an artificially produced lava-like stone), etc., while such other parts as 4, 6, and 32 may be made of Bakelite (a phenol-formaldehyde resin), stainless steel, etc. These latter parts need not be made of materials which are entirely free of tendencies to be pitted or otherwise superficially altered by the combined action of corrosive chemicals and rubbing action of the filaments handled.

It is to be understood that changes and variations may be made without departing from the spirit and scope of the invention as defined in the appended claims.

I claim:

1. Reel mechanism comprising a hollow shaft, a cage-like structure comprising two sets of interdigitating bars parallel to the shaft, means for imparting relative motion between the sets of bars during rotation thereof to provide thread advancing motion, means for rotating the structure as a unit about the axis of the shaft at different speeds comprising two driving members, means for rotating the members at different speeds, and clutch means axially spaced from one end of the cage-like structure for alternately engaging the two driving members rotating at different speeds, means comprising a rigid rotatable and axially movable member extending through the shaft to the other end of the cage-like structure for selectively engaging and disengaging the clutch means with respect to one of the two driving members, and detent means comprising a fixed slotted element exposed at said other end of the reel and a radially extending pin secured to the movable member and extending into the slot of the slotted element for retaining the clutch means in the selected position.
2. Reel mechanism as defined in claim 1 in which the axes of the two sets of bars are eccentric and parallel with respect to each other.

RICHARD W. STANLEY.
